Filed Nov. 23, 1970, Ser. No. 26,120

Term of patent 14 years

Int. Cl. D8—03

U.S. Cl. D8—57

FIG. 1.

FIG. 1 is a front perspective view of nippers showing my new design;

FIG. 2 is a rear perspective view;

FIG. 3 is a front perspective view of nippers showing another form of my new design; and

FIG. 4 is a rear perspective view thereof.

The characteristic feature of the design resides in the configuration and appearance of the rearward and downward extension on the ring-bearing blade.

I claim:

The ornamental design for nippers, as shown and described.
